(57) **CLAIM**

The ornamental design for a network interface device, as shown and described.

DESCRIPTION

FIG. 1 is a front, right-hand perspective view of a network interface device according to our new design shown with the cover in the closed position;

FIG. 2 is a front, right-hand perspective view thereof shown with the cover in the opened position;

FIG. 3 is a front, left-hand perspective view thereof shown with the cover in the closed position;

FIG. 4 is a front, left-hand perspective view thereof shown with the cover in the opened position;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom plan view thereof.
